Fred. Attos.

UNITED STATES PATENT OFFICE.

REUBEN A. McCUALEY, OF BALTIMORE, MARYLAND.

IMPROVEMENT IN HOUSEHOLD IMPLEMENTS.

Specification forming part of Letters Patent No. 116,849, dated July 11, 1871.

To all whom it may concern:

Be it known that I, REUBEN A. McCUALEY, of the city and county of Baltimore and State of Maryland, have invented certain Improvements in a Combination Household-Tool, of which the following is a specification:

The nature and objects of the invention consist in combining, in one implement, a number of devices, each one of which serves a different purpose, and economy is subserved, as it becomes a cheap article of manufacture.

The Figure is a perspective view of my implement or combination household-tool, in which—
a represents the main portion or handle, and
b a fire-rake or poker. *c* is a tack-claw. *d* combines three useful purposes—1st, a stove-plate lifter; 2d, a pot-hook, and 3d, a hammer. At

the other end *e* represents a screw-driver, or it may be used as a pry or ice-breaker.

I am aware of the tool of Samuel A. Barr. This I do not claim, its several parts being arranged differently from mine, and it being wanting in two of my combined devices—screw-driver and poker.

Having thus described my invention, what I claim as new, and desire to secure by Letters Patent of the United States, is—

As a new article of manufacture, a combined household-tool, having its several parts constructed and arranged as shown and described.

REUBEN A. McCUALEY.
